Richard N. Reynolds, 122 Warwick Ave.,
Park Forest, Ill.

Filed June 1, 1965, Ser. No. 85,516

Term of patent 14 years

(Cl. D13—1)

FIG. 1

The dominant features of my design for a drive-in food shop or the like reside in the portions shown in full lines.

I claim:

The ornamental design for a drive-in food shop or the like, substantially as shown and described.
